UNITED STATES PATENT OFFICE.

STERLING ELLIOTT, OF BOSTON, MASSACHUSETTS, ASSIGNOR OF TWO-
THIRDS TO HENRY R. THOMPSON, OF SAME PLACE.

WOOD-TURNING MACHINE.

SPECIFICATION forming part of Letters Patent No. 240,584, dated April 26, 1881.

Application filed September 9, 1880. (No model.)

To all whom it may concern:

Be it known that I, STERLING ELLIOTT, of the city of Boston, county of Suffolk, and State of Massachusetts, have invented certain useful Improvements in Wood-Turning Machines; and I hereby declare that the following is a full and exact description of the same, reference being had to the accompanying drawings, making a part of this specification, of which—
10 Figure 1 is a plan view of the top. Fig. 2 is a view of the cone-pulleys. Fig. 3 shows the end of the entire machine with frame taken away. Fig. 4 is a vertical cross-section of the main arbor, taken on the line *x y* of Fig. 1. 15 Fig. 5 is a cross-section of same on the line *v w* of Fig. 4. Fig. 6 is an end view of the hollow arbor *D*, and shows the anti-friction rollers *K K K*.

The object of my invention is to provide a means by which square pieces of wood of any length may be revolved and fed forward continuously, and at the same time turned to any required design by a vertically-oscillating tool, which is governed in its movements by a revolving cam or former. This is accomplished by means of a hollow revolving mandrel having a square aperture, by passing through which the wood is revolved. A continuous forward motion is imparted to the wood by revolving it within a female screw, which may be fixed, or it may have a rotary motion somewhat slower than that of the timber which is passing through it.

The revolving and feeding mechanism is shown in section at Fig. 4. The feed-screw *L* is supported upon a tube inside the main arbor *D*. In practice it is found necessary to make this screw of a very coarse pitch, in order to avoid splitting off the corners of the wood between the threads of the screw. As the amount of wood which may be safely removed by the cutters at each revolution is much less than the necessary pitch of feed-screw the screw is allowed to revolve with the wood, but at a slower speed, their relative motions being regulated by two pairs of differential gears, *E F* and *e f*. To accomplish this the larger gears *E* and *F* are rigidly attached to a single shaft. The small gear *e* is fixed to the tube *D*, which, by means of its square aperture, revolves the

wood. The small gear *f* is fastened upon the outer end of the inner tube, which tube carries upon its opposite end the feeding-screw *L*; hence it follows that a variation in the relative sizes of the two pairs of gears will make a difference between the speed of the feed-screw and that of the wood within it, which will cause the wood to move forward in proportion to that difference. The first turn or thread of the feed-screw has teeth formed upon its edge like a saw, as shown at *N*, Figs. 4 and 5. These teeth cut a spiral groove upon the four corners of a piece of wood, (just as a screw is cut by a die,) and the remaining threads follow in this groove, causing the wood to move forward. 65 The square aperture in the end of arbor *D* is preferably made of four rollers, as shown in Fig. 6.

G, Fig. 1, is a tapered shell or bearing having a stationary knife, which rounds the wood, leaving its sides parallel, and furnishing a bearing by which the wood is held while being finished by the tool *h*. The finishing-tool *h* is held by the vertically-oscillating tool-holder *H*, as shown in Figs. 1 and 3. The motion of the tool-holder *H* is governed by the cam *I*. As the rotary and forward motions of the timber are uniform, it follows that the length of the handle, chair-round, pen-holder, or other article being turned will be determined by 80 the speed with which the cam *I* revolves. This is regulated by the cone-pulleys *J J*, the position of the belt being maintained by the movable guide *M*.

The mode of operation is as follows: The 85 timber to be operated upon is passed through the hollow mandrel from the end marked *x*, and, after being turned through the feed-screw *L*, is caught and revolved by the rollers *K K K*, which also revolve upon their own centers, 90 and thereby offer less resistance to the forward motion of the wood which they revolve.

What I claim as new, and desire to secure by Letters Patent, is—

1. In a wood-turning machine, the hollow 95 mandrel *D*, having within it the screw-carrying mandrel, in combination with gearing for maintaining between said mandrels a uniform difference of speed, substantially as shown and described.

2. In a wood-turning machine, the vertically-oscillating tool-holder H, in combination with the forming-cam I and cone-pulleys J J, for operating the same, substantially as shown and 5 described.

3. In a wood-turning machine, the combination of the two hollow mandrels D and L, and the differential gears E F and e f, acting together to produce the effect of revolving and

feeding forward the material, substantially as 10 shown and described.

In testimony that I claim the above I have hereunto subscribed my name in the presence of two witnesses.

STERLING ELLIOTT.
